SOAP TABLET COVERED WITH A SOFT SHEATH

Claude Isaac Meyer, Paris, France

Application August 11, 1936, Serial No. 95,392
In France August 13, 1935

11 Claims.

(Cl. 87—23)

This invention relates to soap characterized by the fact that it is provided with flutings or grooves, preferably peripherical, adapted to be manufactured in various forms, the advantages 5 of which will be hereinafter pointed out; the fluted soap being covered with a soft protective sheath to be rolled up as the soap is being used, the resulting bead thus exposing each groove in the chain of grooves in succession.

10 The present invention is an improvement over the soap tablet described and claimed in another application entitled "Manufacture of soap in tablets", filed by me on June 7, 1935, Serial No. 25,488, copending herewith.

15 The fluted soap covered by the sheath, forming the subject of the present invention presents many advantages as follows:

Only the rubbing surface is exposed to contact with liquid, which renders it economical in use;

20 A better grip is offered to the hand which is in contact with the sheath and not with the slippery soap;

In view of air being imprisoned between the sheath and the soap, the soap will float.

25 The annexed figures show by way of example some forms of execution of this invention.

Figure 1 shows in section flutings having a straight, deep profile.

Figures 2 and 3 show some grooves reinforced 30 by ribs forming alveoli in between.

Figures 4 and 5 show some alternative forms of these alveoli.

Figure 6 shows a block in which the outer surface of the ribs between the grooves is at an angle 35 to the plane of the lateral face of the tablet.

Figures 7 and 8 show grooves having oblique sides.

Figure 9 shows a block on which the surfaces between the grooves are provided with small supplementary grooves.

40 In these figures the same reference characters indicate the same parts. 1 designates the grooves in block 2; 3 is the soft sheath; grooves 1, preferably disposed parallel to the rubbing surfaces 2—2', preferably run along the entire periphery of the soap. Of course, these grooves may also be arranged in a spiral fashion, zig-zag, or any other sufficiently flat shape to result only in a slight obliquity in relation to surfaces 2—2' of the soap.

50 Figure 1 shows a form of construction in which the flutings 1 are at right angles to the lateral surface of the block and are sufficiently deep to prevent the soft substance of the sheath 3 or its bead 3' from reaching the bottom, even in case of 55 strong pressure of the sheath on the block. Consequently, enough air remains imprisoned within the flutings to impart buoyancy and assure the floatability of the soap. It is to be well understood that the section of these grooves or flutings 60 may have various outlines.

Figure 2 shows a fluting in cross section and Figure 3 in its central horizontal section m—m. In this form of construction the flutings are reinforced by ribs 6 so as to prevent the substance 5 which is between the flutings from collapsing. One readily conceives that whatever profile is adopted for the ribs 6 there will be between them alveoli 8 of greater or lesser capacity with air imprisoned therein. The ribs 6 may be disposed either in such a manner as to support the sheath 10 3 or its bead 3'—as shown in 6' (preferably with incurved edges adapted to fit the shape of the bead)—or set back with respect to same as shown in 6''.

Alveoli 8 may extend over the entire periphery 15 of the flutings or over only a portion of same; they can be disposed in vertical series one over another or preferably in staggered formation as shown in broken lines on Figure 3, in order to obtain greater solidity, everything else being 20 equivalent.

Figure 4 shows an alternative form in which each fluting is extended inwardly of the block by means of alveoli 8 or 8' or by a continuous groove 8'' narrower than the width of the fluting. The alveoli may be either simply extended from the bottom of fluting 1, as shown at 8, or, as represented in 8' they may be almost as wide as the fluting, with straight sides 11, so as to accentuate the pressure of the sheath 3 or of the bead 3' upon the sides of the alveoli to make up 25 for its deformation resulting from the fact of its not being supported at this point by the bottom of the fluting.

Figure 5 shows an alternative form in which each fluting is provided with more than one row 30 of alveoli 8 or with more than one continuous groove 8''.

Figure 6 shows an alternate form in which the outer surface of the ribs between flutings 1 is oblique in relation to the side faces of the block, so as to have the upper edge 9 of the fluting extending well over the bead 3', said bead remaining accessible from the lower edge; thus forming a "water drop" for the purpose of throwing off 40 the streaming water. The obliquity of said outer surface, enlarges the air spaces and facilitates at the same time the passage of bead 3' from one fluting to a lower one.

Figure 7 shows another alternative form in 50 which the upper face of flutings 1 is directed at a slant with respect to the rubbing surface 2' so as to prevent, in case of wear reaching the upper edge of the fluting (line 2—a), the sudden collapse of the block substance which can 55 be used until the wearing surface is down to bead 3' (line 2—b).

Figure 8 shows a form in which the flutings 1 are deep and disposed obliquely in relation to the rubbing surface 2' so as to cause the bead to sink 60

down in each fluting gradually so the wear of the upper face of the fluting progresses. When the bead begins to project beyond the rubbing surface the user realizes from a little added friction 5 that it is time to pass the bead on to the lower fluting before it slips over the rubbing surface.

Figure 9 shows still another alternative form in which the outer surfaces of the ribs between the flutings are provided with grooves 10 parallel or 10 slightly oblique in relation to the longitudinal axis of the flutings 1 or else are provided with 15 knurled indentations affording ventilation and improving the grip of the hand, while watertightness is increased owing to stronger pressure 15 of the sheath due to the diminished surface of contact.

It is obvious that in all the constructional forms shown (Figures 6 to 9), it is possible to provide the alveoli 8 previously described—as indicated 20 in dotted lines in these figures.

It will be observed that in all the examples shown the soap is provided with flutings which cooperate with the sheath in insuring an absolutely water tight enclosure for that part of the 25 soap which is not in use. The tightness of the closure is essential in order to prevent water from penetrating between the soap and the sheath and softening and dissolving part of the soap covered by the sheath.

Such tightness is obtained by causing the bead 30 of the sheath to press against the edges only of the flutings in the examples of Figs. 1, 2, 8, and by causing the bead to press against the bottom of the flutings while the sides of the flutings extend 35 well beyond the bead and cause drippings to fall externally of the sheath in the examples of Figs. 6 and 7. The flutings must be relatively wide in order to thus cooperate with the sheath, so that they could not of themselves 40 act as air traps except possibly at the points where alveoli such as 8, 8" are provided—but in order to insure floatability of the soap it is necessary to provide air pockets of sufficient size to counterbalance the difference in density between the soap 45 and the water, so that the sheath here also performs the new function of cooperating with the flutings in forming air pockets capable of providing the necessary buoyancy. Furthermore, the sheath forms an effective closure for such air 50 pockets, absolutely preventing the escape of air which would be likely to take place even if recesses of relatively small size, such as alveoli 8, 8" were used to trap the air, without providing a positive closure therefor.

It is to be well understood that the constructional forms described above and shown are given only by way of example and may vary to a large extent, without affecting the characteristic features of the invention claimed below.

I claim:

1. In combination with a soap tablet, a pliable water-proof protective sheath adapted to be rolled up and down along the lateral faces of said tablet and having a free edge formed with a rolled 65 bead, said lateral faces being formed with flutings extending peripherally all around the tablet, so that said rolled bead increases in diameter and can be accommodated at each of the successive flutings according as the tablet is worn away 70 from the surface from which said sheath is rolled up, said flutings having a width less than the

diameter of said roll and a depth greater than the penetrating portion of said roll, whereby said sheath forms closed air pockets in said flutings.

2. In combination with a soap tablet, a pliable water-proof protective sheath adapted to be 5 rolled up and down along the lateral faces of said tablet and having a free edge formed with a rolled bead, said lateral faces being formed with flutings extending peripherally all around the tablet, so that said rolled bead increases in diameter and 10 can be accommodated at each of the successive flutings according as the tablet is worn away from the surface from which said sheath is rolled up, said flutings being so dimensioned in width and depth that the sheath does not extend to the 15 bottom thereof under normal air and water pressure, whereby said sheath forms closed air pockets in said flutings.

3. The combination recited in claim 2, further characterized by spaced reinforcing ribs formed 20 in said flutings and joining the walls thereof.

4. The combination recited in claim 2, further characterized by each of said flutings being extended into the tablet in the form of a relatively 25 narrower cavity.

5. The combination recited in claim 2, further characterized by said flutings having straight parallel walls at the mouths thereof to accentuate the pressure of said sheath.

6. The combination recited in claim 2, further characterized by the external surfaces of said tablet being oblique between the flutings in relation to said lateral faces.

7. The combination recited in claim 2, further characterized by the upper faces of said flutings 35 being oblique in relation to the rubbing surface of said tablet.

8. The combination recited in claim 2, further characterized by said flutings being disposed obliquely to the rubbing surface of said tablet. 40

9. The combination recited in claim 2, further characterized by the external surface between the flutings being formed with indentations having substantially less depth than said flutings.

10. A soap tablet having an end wearing surface and lateral faces substantially at right angles thereto, said tablet being adapted to be provided with a pliable protective sheath to be rolled up and down along its lateral faces, said lateral faces being formed with flutings substantially 50 parallel to said wearing surface and extending along the entire periphery of said tablet, so that the roll of said sheath can be accommodated in each of the successive flutings according as the tablet is worn away from said wearing surface, the 55 external surfaces of said tablet being oblique between the flutings in relation to said lateral faces.

11. A soap tablet having an end wearing surface and lateral faces substantially at right angles thereto, said tablet being adapted to be provided with a pliable protective sheath to be rolled up and down along its lateral faces, said lateral faces being formed with flutings substantially 60 parallel to said wearing surface and extending along the entire periphery of said tablet, so that the roll of said sheath can be accommodated in each of the successive flutings according as the tablet is worn away from said wearing surface and having spaced reinforcing ribs formed in said 65 flutings and joining the walls thereof.

CLAUDE ISAAC MEYER.
